MILTON O. SCHUR, OF BERLIN, NEW HAMPSHIRE, ASSIGNOR TO BROWN COMPANY, OF BERLIN, NEW HAMPSHIRE, A CORPORATION OF MAINE

METHOD OF AND APPARATUS FOR DELIVERING PULP STOCK AT CONSTANT TONNAGE RATE

Application filed November 14, 1930. Serial No. 495,599.

This invention relates to a method of and apparatus for delivering pulp stock at a constant tonnage rate.

In the manufacture of several articles or substances from wood pulp it is highly important that the pulp be supplied at a constant tonnage rate, that is, that the dry weight of the pulp delivered for a unit of time should be substantially constant with a very small maximum variation. This is especially important where the pulp is to be treated with measured quantities of chemicals. It is a relatively simple matter to supply a constant volume of pulp stock. By regulating the consistency of such stock so as automatically to maintain the consistency substantially uniform, a substantially constant tonnage rate of delivery can be obtained. In combining the two steps so as to obtain a constant volume rate of stock having a constant consistency, several practical difficulties are encountered. It is an object of this invention to provide apparatus which avoids such difficulties and which is capable of delivering pulp with only slight variations in the tonnage rate.

The present invention includes improvements over the subject matter of my Patent No. 1,744,145 granted January 21, 1930. In ordinary mill practice the consistency of pulp stock supplied from storage tanks is liable to vary from time to time owing to a variety of causes such for example as local dilution caused occasionally by wash water used in cleaning out the beater. Furthermore, one day's run of stock may differ materially in consistency from that of another day so that it is necessary to regulate the consistency of stock supply in order to insure uniformity. To this end the stock which is supplied from the beater must be thicker than that which is delivered at a constant tonnage rate since the consistency is, according to the present invention, regulated by diluting the supplied stock and controlling the rate of addition of the diluted water. In the apparatus described in my Patent No. 1,744,145, diluting water is mixed with the supply stream of stock, the diluted stock being pumped into a vat or tank from which it is metered at a constant rate. The excess diluted stock escapes over a suit-

able dam and flows back to the supply tank from which it was pumped. This results in a dilution of the stock in the supply tank. This is undesirable as it introduces an additional factor of variation in the supply stream of stock to be diluted. According to the present invention a valve is supplied to control the rate of flow of diluted stock into the metered vat so that the diluted stock will enter the vat at substantially the same rate at which it was metered therefrom. The regulating valve, besides obviating unnecessary variation in the consistency of the supply stream of stock also effects a considerable saving in the power required to drive the pump for the supply stream. Pumps of the centrifugal type are frequently used for streams of pulp stock. It is characteristic of this type of pump that when working against a closed valve, less power is required to operate the motor of the pump than when a valve is open, this being due to the fact that when no liquid is being discharged from the pump, the liquid within the pump casing merely flows around with the paddles. When, however, the valve is open, velocity must be imparted to the incoming stream of liquid to discharge it through the discharge pipe. This requires considerably more power than that required for merely maintaining a circular flow of a small amount of liquid within the pump casing.

In my Patent No. 1,744,145, a consistency regulating device is described in which a movable feeler is supported in the stream of diluted stock entering the metering vat. This type of consistency regulator is substantially unaffected by changes in velocity of flow of the stream through a considerable range. According to the present invention, I may employ a simpler type of consistency regulator which can be used in a sampling stream of constant velocity by also providing apparatus by which a portion of the stream of diluted stock entering the metering vat is diverted and caused to flow past the feeler of the regulator at substantially constant speed. This makes possible a considerable simplification of the apparatus. A constant velocity of flow of the sampling

stream past the feeler is maintained by a positive feed of the sampling stream at a constant volume rate of flow, preferably at a point beyond the feeler so that the feeler can be located as close as possible to the point at which diluting water is admitted into the supply stream of stock. The constant volume rate of feed may be obtained by a metering device driven at constant speed. The metering device may be a type widely used for feeding pulp stock at a constant volume rate by means of a wheel revolving on a horizontal axis to present to the pool successive compartments formed by a number of paddles. To avoid the sticking of pulp in the angles between successive paddles in a wheel of small size such as is suitable for use in a sampling stream, I may block off or fill the space between paddles for a short distance from the core of the wheel.

The function of the consistency regulator is to control a supply of diluting water which is added to the incoming stream of stock so as to maintain automatically a substantially constant consistency in the stock entering the metering vat. In order to control the rate of inflow of diluted stock into the vat, the supply stream may be controlled by a suitable butterfly valve automatically movable in response to changes in the direction of variation of the level of a float on the pool of stock within the vat. The valve may be located at any convenient point, either in the supply stream of undiluted stock or in the stream of diluted stock as it is about to enter the vat. According to the present invention mechanism is provided for handling large streams of pulp. This includes power means for operating the valve, and automatic controls for the power means responsive to changes in the direction of variation of level of the pool of stock in the vat. In general, where the opening of a gate or valve in a stream of fluid is automatically varied in response to variations from a mean value of some characteristic of a portion of the fluid beyond the valve, such as the pressure or velocity of the fluid at a given point, or as in the present instance the surface level of a pool, the mechanism for automatically controlling the valve usually causes the valve to move in a direction to oppose a change in pool level from the mean height. This corrective operation of the valve continues until the level returns to the mean height. Thus, if the pool rises, the control mechanism starts to close the valve and continues to close it not only after the pool level has started to fall, but until the level has fallen back to the mean height. By that time the valve has been shut too far, and the level falls rapidly below the mean height, starting the control mechanism to move the valve toward its open position. Thus there is a tendency on the part of the automatic controlling

apparatus to fluctuate violently from one extreme to the other so that the purpose of the apparatus is largely defeated. According to the present invention, this tendency to fluctuate or "hunt" is reduced to a slow drift between relatively narrow limits by the use of a frictional connection between a member movable directly in response to changes in the characteristic to be kept constant and control mechanism for adjustably moving the valve. In the present instance the directly movable member may be a float on the surface of the pool of pulp stock in the vat.

Rapid and efficient mixing apparatus is also provided according to the present invention to insure a thorough intermixing of the diluting water with the supply stream of pulp. Aqueous suspensions of wood pulp, especially those of relatively thick consistency, appear to have an aversion to dilution. Ordinary mixing of diluting water with pulp stock will not produce a diluted stock of uniform consistency since the stock and water tend to maintain themselves in separate bodies. To overcome this reluctance on the part of the stock to intermix with diluting water, I employ means for violently agitating the stock and diluting water in a suitable mixing tank, the agitating means being capable of forming rapid, turbulent currents in the stock in such a manner that there is up and down mixing as well as transverse mixing. In this way the diluting water is quickly intermixed with the stock and the diluting effect of the water upon the consistency of the stock stream is quickly felt at the point of discharge from the mixing tank. This makes for increased sensitivity in the apparatus as a whole, which is an important and valuable feature. Further to increase this sensitivity, the feeler element of the consistency regulator is preferably located close to the outlet of the mixing tank so that the lag between a change of the supply rate of the diluting water and its effect on the feeler is reduced to a minimum.

For a more complete understanding of the invention reference may be had to the description thereof which follows and to the drawings of which,—

Figure 1 illustrates diagrammatically apparatus embodying the invention.

Figures 2, 3 and 4 are similar views of modified forms of the invention.

Figure 5 shows diagrammatically hydraulic apparatus for controlling the stock level in the metering vat.

Figure 6 shows on a larger scale a portion of the mechanism shown in Figure 5.

Figure 7 shows a modified form of a portion of the invention.

Figure 8 is a perspective view of a modified form of feeler for consistency regulator.

Referring in detail to Figure 1, 10 represents a supply tank for pulp stock coming

through a supply pipe 11 from a storage tank (not shown) or directly from a beater. Within the tank 10 are a suitable number of agitators 12 driven by a motor 13 to prevent settling of the fibers and also to average up the consistency of the stock received through the pipe 11. The tank 10 is preferably of considerable capacity so that there is no abrupt fluctuation in the consistency of the stock taken therefrom. From a point near the bottom of the tank 10 a discharge pipe 14 runs to a centrifugal pump 15. A second pipe 16 leads from a point about halfway up on the side of the tank 10 to the pump 15. The pipes 14 and 16 may be controlled respectively by suitable valves 17 and 18. Ordinarily stock is taken from the middle level of the tank 10 through the pipe 16, the pipe 14 being used when it is desired to empty the tank or in case the level should temporarily fall below the orifice of the pipe 16. The pump 15 discharges into a pipe 20 which opens into the bottom of a suitable mixing tank 21. Within the pipe 20 is a valve 22 preferably of the butterfly type which provides a variable supply port for the admission of liquid into the tank 21. The valve member itself may be in the form of an elliptical plate which fits diagonally across the cylindrical interior of the pipe when the valve is entirely closed and may be swung to a position in line with the axis of the pipe by a suitable lever 66 which may be operated by any convenient apparatus such as an hydraulic piston contained in a cylinder 24. Within the mixing tank 21 suitable mixing apparatus may be provided. As shown, this may consist of a pair of marine propellers 25 mounted on a shaft 26 supported a short distance above the bottom of the tank 21. This shaft may be connected to a suitable motor 27 for rotation. The blades of the propellers 25 are preferably of opposite pitch so that they throw streams in opposite directions against the sides of the tank. This causes a pair of circular currents rising at opposite sides of the tank, meeting at the top and descending in the center portion of the tank. The propellers are preferably driven at high speed so that a thorough and rapid churning and mixing effect is obtained, the mixing being both lateral and up and down. Just below the point where the pipe 20 enters the bottom of the tank 21, a water pipe 30 joins it. Thus the stock is supplied with diluting water at a point just prior to its entrance into the mixing tank. As soon as the stock enters the mixing tank, the rapid mixing currents carry it laterally and upwardly, the propellers churning the thick stock and the water together to form quickly an evenly diluted stock. If the rate of supply of water through the pipe 30 is increased or diminished, this change is almost immediately felt at the upper end of the mixing tank 21 by reason of the rapid circulation of the currents in the tank 21. The diluting water is supplied through a suitable pipe 31 which is connected to a standpipe 32. From the latter a series of overflow pipes 33 lead off at different levels, any one of these overflow pipes being left open as desired to give a corresponding constant head of water in the pipe 30. The upper end of the standpipe 32 is open to permit the escape of any bubbles which may enter through the pipe 31. A control valve 34 is located in the pipe 30, this being automatically controlled as herein-after described in detail so as to maintain a substantially constant consistency in the stock passing through the mixing tank 21.

At the upper end of the tank 21 a short standpipe 35 projects upwardly into a metering vat 36 at one end of which is a metering wheel 37. The metering wheel 37 may be similar to that described in my Patent No. 1,744,145, and may have a number of blades or paddles between which are the compartments successively filled by pulp from the pool in the vat 36 as the metering wheel rotates. The pulp stock passing through the wheel is discharged into a suitable pipe 38 through which it is conducted to apparatus for further treatment. Within the vat 36 is a dam 40 to provide a spill-way in case of excessive high level of the pulp stock in the pool. Excess stock spilling over the crest of the dam 40 may be conducted through a pipe 41 back to the supply tank 10. Ordinarily, however, the surface level of the stock pool in the vat 36 will be automatically maintained by the valve 22 below the crest of the dam 40 so that no diluted stock will be returned to the supply tank 10.

For the control of the valve 22, suitable mechanism may be provided including a float 42 in the pool of stock in the vat 36. This control mechanism may take various forms. For example, hydraulically operated control apparatus is illustrated in Figures 1 and 6. As shown, the float 42 may be connected by a rod 43 to a lever arm 44 which may be pivoted as at 45. This arm carries a pair of spring-pressed friction members 46 and 47 adapted to press against opposite side surfaces of the vertical stem 50 of a slide valve 51. The pressure of the friction shoes 46 and 47 may be provided by a pair of springs 52 and 53, the force of which may be regulated by a pair of adjusting screws 54 and 55. The stem 50 has a neutral or normal position relative to the arm 44. A pair of springs 56 and 57 connect the stem 50 with the arm 44 in such a way as to tend to maintain the stem in its neutral position and to return the stem to its neutral position relative to the arm whenever it is displaced therefrom in either direction. This restoring action on the part of the springs 56 and 57 is frictionally opposed by the friction shoes 46 and 47. The

valve 51 may slide in a suitable casing 60 and may be provided with suitable ports in a manner well known in the art by which a pressure fluid supply pipe may be connected with either one of two service pipes, the other service pipe being simultaneously connected with a discharge pipe. As shown, compressed liquid or air may be supplied through a supply pipe 61, a discharge pipe 62 being also connected with the casing 60. A pair of service pipes 63 and 64 extend from the casing 60 to the hydraulic cylinder 24 so as to transmit fluid pressure to the chamber above or below a piston 65 in the cylinder 24 for the actuation of the valve 22. The piston 65 may be connected with the valve 22 by any suitable linkage such as a lever arm 66 as shown in Figure 1, or a gear train as shown in Figure 5. The friction shoes 46 and 47 are provided for the purpose of steadyng the operation of the valve 22 and preventing the apparatus from hunting. This maintains the stock level in the vat 36 at a substantially constant level, there being a slow drift between predetermined maximum and minimum limits, which limits may be quite close together so there is little variation in the level of the pool.

The operation of the valve control apparatus is as follows: Considering first, by way of comparison, what would happen if the stem 50 were pivoted directly to the arm 44 instead of frictionally connected through the shoes 46 and 47, it is evident that a rise or upward drift in the level of the pool would cause a rise in the float 42 and the stem 50. This would cause the valve 51 to admit pressure fluid into the service pipe 64 so as to move the valve 22 toward its closed position and thus to diminish or constrict the supply port for the incoming stream of stock. When the valve 22 had been closed sufficiently to stop the rise of the pool level, the valve 51 would still be open and would remain open until the level of the pool dropped to normal. During the dropping of the pool level to normal, however, the valve 22 would still be closing so that by the time the valve 51 was closed to stop further closing motion of the valve 22, the level of the pool would be dropping rapidly owing to the excessive closing of the valve 22. This would carry the pool level below normal, resulting in the operation of the valve 51 to move the valve 22 toward its wide open position. This opening motion would continue until the pool surface was back to normal level. Thus the level of the pool would fluctuate violently through a wide range. Stabilization, however, may be accomplished by the frictional connection between the valve stem 50 and the lever arm 44. If with the arm and stem thus connected, the level of the pool should rise owing to an oversupply of incoming stock, the float 42 would rise and would elevate the stem

50 sufficiently to open the valve 51 for the admission of pressure to the pipe 64. This would cause the piston 65 to move the valve 22 toward its closed position, constricting the supply port. The upward or downward movement of the stem 50 is stopped by engagement of the valve 51 with an end of the casing 60 when the valve 51 is fully open. During the closing movement of the valve 22 the float 42 would continue to rise until the decrease in the supply stream of stock was sufficient to stop such rise and to start a recession or downward drift of the level. During the rise of the float 42 the stem 50 is carried upwardly therewith until its motion is stopped by engagement of the valve 51 with the upper end of the casing 60. Further rising of the float 42 then results in a slipping of the friction shoes 46 and 47 on the sides of the stem 50 and an elongation of the spring 57.

As soon as the level of the pool starts its downward drift, the stem 50 is at once pulled downwardly by its frictional engagement by the arm 44 so that the valve 51 is closed and the further closing of the valve 22 is at once stopped. This maintains the supply port unchanged until the valve 22 is further actuated. Since the level of the pool is slightly dropping when the valve 51 is closed, it will ordinarily continue to drift downwardly, but at a slow rate. Meanwhile the tension of the spring 57 will tend to elevate the stem 50 to its normal position with respect to the arm 44, this normal position having been disturbed by additional rise of the arm 44 after the stem had reached its upper limit. If the rate of descent of the pool level is very slow so that the upward motion of the stem 50 caused by the spring 57 is faster than the downward motion of the stem caused by the descent of the arm 44, the valve 51 may be again actuated to close the valve 22 a little further, and hence to cause an additional constriction of the supply port. If, however, the descent of the pool level is at such a rate as to balance the rise of the stem 50 under the action of the spring 57, the pool level will return to its normal height by a gradual fall and at the same time the stem 50 will return to its normal position relative to the arm 44 without further change in the supply port. If the fall of the pool level should be at an excessive rate, i. e., more rapid than the elevation of the stem 50 by the spring 57, then the valve 51 is operated to cause opening motion on the part of the valve 22 which would enlarge the supply port and tend to check the fall in the level of the pool even before it reached its normal position. A fall of the level of the pool below its normal height would result in similar operation of the apparatus but in the opposite direction. It is evident that with such apparatus, properly

adjusted, the variation of level in the pool may be restricted to a slow drift between relatively narrow limits.

The foregoing description of the operation is based on the assumption of a quiet surface on the stock pool. As a matter of fact this condition does not usually obtain in a vat from which stock is being taken by a metering wheel such as the wheel 37. In the operation of this wheel the stock in the pool rushes into successive compartments so that there is a surging of stock in the pool which causes the float 42 to bob up and down constantly. This results in an oscillation of the stem 50 up and down and a slight resulting oscillation of the valve 22 as the control valve 51 is alternately opened in opposite directions. A rise or fall in the average level of the pool, however, will result in an elevation or depression of the average height of the stem 50 so that in the case of a rise, for example, the brief periods of pressure in the pipe 64 would be slightly longer than the periods of pressure in the pipe 63 and there would thus be a resultant movement of the valve 22 toward its closed position. This oscillating movement of the float 42 and of the parts connected therewith does not interfere with the effectiveness of the frictional connection between the stem 50 and the arm 44 which keeps the mean level of the pool limited to a slow drift within a narrow range. The constant motion of the float 42 moreover assists the action of the shoes 46 and 47 and the springs 56 and 57 since any tendency on the part of the shoes to stick against the sides of the stem 50 is thus obviated. This mechanism which responds promptly to changes of level of the mean surface of the pool when it is at any level rather than at only normal level, is particularly important where the level is liable to be changed not only by the rate of supply of undiluted pulp from the tank 10 but also the rate of supply of diluting water from the pipe 30. It is obvious that if the consistency of the stock delivered from the tank 10 increases, the water supply through the pipe 30 must also increase to dilute the stock to its desired consistency. This will result in a rise in the pool surface and a consequent movement of the valve 22 toward its closed position.

The rate of supply of diluted water from the pipe 30 may be automatically controlled by such consistency regulating apparatus as is illustrated and described in my Patent No. 1,744,145. A somewhat different form of consistency regulating apparatus is illustrated in Figures 1 and 3. Referring to Figure 1 a relatively small sampling pipe 70 may be mounted within the supply pipe 35, this sampling pipe 70 leading from the outlet of the mixing tank 21 into a miniature vat 71 from which the stock may be metered

by a metering wheel 72. The metering wheel 72 for the sampling stream is small compared with the metering wheel 37 for the vat. In the small wheel, pulp is liable to wedge and stick in the angle between the paddles, thus changing the capacity of the wheel. To obviate such sticking, I may fill or block off, as at 69, the spaces between the paddles for a short distance from the core of the wheel. The vat 71 is set at such a height that the surface of the stock pool therein will have the same level as the stock spilling over the top of the pipe 35, that is, a substantially constant level. By rotating the metering wheel 72 at a constant rate, the rate of discharge of stock from the vat 71, and hence the rate of admission of stock thereinto, will be constant. Thus a constant velocity of flow may be maintained in the pipe 70. In this flow of constant velocity I may support a suitable feeler 73 in the shape of a ball as shown in Figure 1, or in any other convenient shape such as the horizontal rod 730 shown in Figure 8. In order to obtain maximum sensitivity in the apparatus, the orifice of the sampling pipe 70 is located in the outlet of the mixing tank 21, and the feeler 73 is located as near as possible to the orifice so as to be in a position to react as soon as possible to a change in the consistency of the stock leaving the mixing tank. The feeler may be located a short distance above the orifice of the sampling pipe to avoid uncertainty of its operation arising from turbulence of the sampling stream at the orifice of the pipe. The feeler is mounted on a supporting stem 74 which may be attached to a lever arm 75 pivoted at one end as at 76. The stream of stock rising through the pipe 70 flows against the feeler 73 and pushes it upwardly against a suitable spring 80. The spring may be adjusted to balance any desired thrust of the feeler 73 according to the stock consistency desired, by an adjusting screw 81. If the velocity of the stream in the pipe 70 is maintained constant by operating the metering wheel 72 at a constant rate, the upward pressure of the stream against the feeler 73 will vary as the consistency of the stock. If the stock becomes thicker, it will push more strongly on the feeler 73 and will swing the lever arm 75 upwardly, whereas a thinning of the stock in the pipe 70 will permit the arm 75 to swing below its normal position. Suitable mechanism may be provided to regulate the action of the valve 34 for the diluting water in accordance with the motions of the arm 75. For example, the valve 34 may be opened and closed by a reversible electric motor 82 controlled by a double throw switch connected with or including the free end of the arm 75. As shown, on the arm 75 is a contact member 83 which is adapted to contact with a point 84 when the arm swings up, and with a 100

point 85 when the arm swings down. These points are connected with a source of electric energy and with the motor 82 in such a way as to cause the motor to run in a direction to shut the valve 34 when the contact member 83 touches the point 85, and to cause the motor to run in a direction to open the valve 34 when the member 83 touches the point 84. By locating the points 84 and 85 close together the apparatus can be made to respond at once to very slight variations in the consistency of the diluted pulp. If, for example, the pulp supplied from the tank 10 thickens slightly in consistency, the additional push on the feeler 73 closes the switch 83, 84 causing the motor to open the valve 34 wider to admit diluting water to the mixing tank 21 at an increased rate. The effect of this increase of diluting water is quickly felt in the pipe 70 owing to the rapid circulation and churning of the pulp and water within the mixing tank 21. As a result, the opening motion of the valve 34 is quickly stopped when the consistency of the stock in the mixing tank 21 has been restored to the desired value. The maintaining of a strictly constant velocity of flow in the pipe 70 is important in that it permits the use of the simple consistency regulating apparatus shown in Figure 1 in place of more elaborate apparatus which is necessary for successful operation in currents of varying velocity. A regulator of the latter type is illustrated in my Patent No. 1,744,145.

In Figure 2 is illustrated a slightly modified apparatus, the chief difference being in the means for supplying undiluted pulp from the supply tank 10 to the mixing tank 21. Instead of an automatic valve 22 as shown in Figure 1, I may extend the supply pipe 20 into a suitable tank 79 from which a pipe 86 leads into the bottom of the mixing tank 21. The diluting water is introduced into the pipe 86 through a pipe 87 which enters the pipe 86 at a point adjacent to the mixing tank 21. The flow of water through the pipe 87 may be controlled by a suitable valve 88 which is actuated by a consistency regulating apparatus responsive to a rotating paddle or feeler 90, this type of consistency regulating apparatus being similar to that described in my Patent No. 1,744,145. A suitable dam 91 is provided in the compartment 79 to provide the spill-way for excess stock which is pumped into the compartment 79. This excess is led back to the supply tank as through a suitable pipe 92. As the feeler 90 of the consistency regulating apparatus 89 is not appreciably affected in its operation by moderate changes of flow in the stream in which it works, it may be supported directly in the stream of stock entering the vat 36.

As shown, however, it may be supported instead in a sampling stream leading into a

sampling vat 71 from which the stock is metered at a constant rate by the metering wheel 72, this metered stock being conveniently discharged into the return pipe 92 which leads to the supply tank 10. The quantity of diluted stock returned to the tank 10 through the sampling meter 71 is not sufficient to affect the average consistency of stock in the tank 10 appreciably. This combination of a rotating feeler and a sampling stream may be used where an extraordinarily high degree of accuracy in the control of stock consistency is desired.

In Figure 3 an electric apparatus for controlling the position of the valve 22 is illustrated, the remainder of the apparatus therein shown being substantially identical with that illustrated in Figure 1. The valve 22 is located in the stock supply pipe 20 and is operable by a suitable electric motor 95 through a train of gears 96. For controlling the motor 95 a two-way switch may be employed, this switch including a movable member 97 adapted to come into contact with a pair of contact points 98 by upward motion or into contact with a pair of contact points 99 by downward motion. The switch member 97 may be carried on a stem 50 which may be frictionally connected with a lever 44 as hereinbefore described. The motor 95 is of any convenient reversible type, the field windings of the motor being connected respectively with the contact points 98 and 99 in such a manner as to operate the motor in one direction or the other according as the switch member 97 makes contact with either set of points. To prevent accidental over-running of the motor 95 which might result in damaging the valve apparatus, I may provide suitable limiting switches 100 and 101. These switches normally close gaps in the circuits through the points 98 and 99 respectively. If the valve 22 is moved to its fully opened position, a pin 102 engages the switch 101 and opens it, thus breaking the circuit tending to operate the motor 95 in the direction to open the valve 22. In like manner, if the motor 95 moves the valve 22 to its fully closed position, the pin 103 is provided to engage the switch 100 and thus to stop the further action of the motor in this direction.

In Figure 4 the electrically operated mechanism for controlling the valve 22 is combined with an electrically operated consistency regulating apparatus. This apparatus may include mechanism similar to that described in my Patent No. 1,744,145, the control portion of the apparatus being contained in a suitable casing 110. Variations in the resistance offered by the stream of stock to the rotation of the feeler 90 cause electric contacts to be made for the operation of a motor 111 in one direction or the other to vary the opening of a suitable valve 112.

through which water is supplied to the stream of stock entering the mixing tank 21. The operation of this apparatus is substantially the same as that of the apparatus illustrated in Figure 1.

5 A modified form of apparatus for controlling the valve 22 is shown in Figure 7. The lever arm 44 shown in most of the figures may be dispensed with, and the vertical rod 43, which is secured to the float 42, may extend through a pair of suitable guides 120 and 121. A friction collar 122 is lightly clamped on the rod 43 between the guides 120 and 121 as by adjustable springs 123. The collar 122 carries an arm 124 on which are mounted a pair of bunters 125 and 126 adapted to engage and rock respectively a pair of mercury switches 130 and 131 of a well known type. Each of these switches is normally held open by a spring 132. The switches are adapted to be connected to an electric motor for operating the valve 22 in lieu of the switches illustrated in Figures 3 and 4 for this purpose. In the operation of the apparatus, if the float causes the rod 43 to rise, the bunter 125 rocks the switch 130 to close it. This starts the motor 95 operating in a direction to close the valve 22. The guide 120 may carry an adjustable stop 135 to stop the upward movement of the collar 122 and arm 124 at the point where the bunter 125 opens the switch 130. If the rod 43 continues to rise, it slips through the collar 122 which is frictionally mounted thereon. Meanwhile the motor 95 is operating to reduce the incoming stream of stock and thus to lower the stock level in the vat 36. As soon as the level starts to fall, the collar 122 descends with the rod 43 and the switch 130 is thereupon opened by its spring 132, stopping the motor 95. This prevents the closing action of the valve 22 from being carried too far. There will customarily follow a slow downward drift of level until the bunter 126 closes the switch 131 and starts the motor 95 operating to open the valve 22 wider. As soon as the level starts to rise, the motor 95 is stopped. This prevents undesirably violent fluctuations of the level of the stock in the metering vat.

50 I claim:

1. Apparatus of the class described comprising a vat for pulp stock having an outlet port and an inlet port, means for controlling the outflow of stock through said outlet port, and means for automatically maintaining a substantially constant consistency and volume rate of inflow of stock through said inlet port.

2. Apparatus of the class described comprising a vat for pulp stock having an outlet port and an inlet port, means for controlling the outflow of stock through said outlet port, means for automatically controlling the volume flow of stock entering the vat through

said inlet port, means for introducing diluting water into the stock stream entering the vat prior to its passage through said inlet port, and means for mixing said diluting water into said stock stream to secure an even distribution of the pulp fibers through the watery vehicle of the stock passing through said inlet port.

3. Apparatus of the class described comprising a stock vat having an inlet port and an outlet port, means for discharging stock through said outlet port at a predetermined rate, means for maintaining a flow of stock into said vat through said inlet port, means for automatically controlling at a point spaced from said inlet port the volume flow of said stream in accordance with the volume of stock in the vat, means for admitting diluting water to said stream of stock at a point between the point of control of said stream of stock and said inlet port, and means responsive to the consistency of the stock passing through said inlet port for automatically controlling the volume flow of said stream of diluting water.

4. Apparatus of the class described comprising a pulp stock vat having an inlet port and an outlet port, means for causing a substantially constant flow of stock from said vat through said outlet port, automatic means for maintaining an inflow of stock through said inlet port substantially equal to said outflow, and means for automatically maintaining a substantially uniform consistency in said inflowing stock, said last named means including means for introducing diluting water into said inflowing pulp stream prior to its passage through said inlet port, means for automatically controlling the supply of said diluting water in accordance with the consistency of the pulp passing through said inlet port, and means for thoroughly mixing said diluting water into the pulp stock stream prior to its passage through said inlet port.

5. Apparatus of the class described comprising a vat for pulp stock having an inlet for the inflow of stock, a conduit for the stream of pulp stock inflowing into the tank, a water pipe discharging into said conduit to dilute the stock stream, a consistency regulator responsive to the consistency of the stock entering the vat for controlling the flow of diluting water into said conduit to maintain the consistency of the entering stock substantially constant, a valve in said conduit at a point upstream relatively to the water pipe connection, and means for regulating said valve automatically in response to the quantity of stock in said vat.

6. Apparatus of the class described comprising a vat for pulp stock having an inlet for the inflow of stock into the vat, means for leading off a sampling stream of substantially constant velocity from the inflowing stream of stock, means for automatically

regulating the consistency of the stock in said inflowing stream, said regulating means including a feeler immersed in said sampling stream, and means for metering stock from said vat at a predetermined rate.

7. Apparatus of the class described comprising a vat for pulp stock having an inlet for the inflow of stock into the vat, means for leading off a sampling stream of stock from the stream entering the vat, means for automatically regulating the consistency of the stock in said inflowing stream, said regulating means including a feeler immersed in said sampling stream, mechanism for maintaining the flow of said sampling stream at a constant velocity, said feeler being located upstream relatively to said mechanism, and means for metering stock from said vat at a predetermined rate.

8. Apparatus of the class described comprising a vat for pulp stock, means for metering stock from said vat at a constant volume rate, a mixing box communicating with said vat to supply stock thereto, means in said box for rapidly and continuously mixing the contents thereof, means for supplying a stream of stock to said box, means for supplying water to said box to dilute the stock supplied thereto, means responsive to changes in consistency of stock leaving the box for automatically regulating the water supply to maintain the stock passing from the box to the vat at a substantially constant consistency, and means responsive to changes in the level of stock in the vat for automatically regulating the rate of delivery of stock to the vat.

9. Apparatus of the class described comprising a vat for pulp stock, means for metering stock from said vat at a constant volume rate, means for supplying a stream of stock to said vat including a mixing box adjacent to said vat, means for supplying diluting water to said box, means in said box for mixing thoroughly the supplied stock and diluting water and for circulating the mixture rapidly in the box, means for automatically regulating the rate of flow of stock entering the box and vat to maintain the quantity of stock therein substantially constant, and means for regulating the supply of diluting water to maintain the consistency of the stock flowing into the vat substantially constant, said water regulating means including means for leading off a sampling stream of diluted stock from said box at a constant velocity, and a feeler supported in said sampling stream.

10. Apparatus of the class described comprising a consistency regulator having a feeler to be supported in a stream of stock, and means for maintaining a constant velocity of flow in the portion of the stream contiguous to said feeler.

11. Apparatus for regulating the consistency of a delivery stream of pulp stock, which includes means for leading off from said de-

livery stream a sampling stream of stock, a feeler in said sampling stream, means for positively feeding said sampling stream at a constant volume rate of flow, and mechanism responsive to the resistance of said feeler to the flow of the stock in said sampling stream for altering the consistency of the stock in said delivery stream.

12. In combination with apparatus for leading off a sampling stream of pulp stock to test and regulate the consistency thereof, means for positively feeding said sampling stream at a constant volume rate of flow, said means comprising a metering device, and means for driving said device at a constant rate.

13. Apparatus for maintaining substantially constant a characteristic of a portion of a stream of fluid depending on the rate of supply of fluid to said portion of the stream, which comprises a member movable in response to changes in said characteristic, means for regulating said rate of supply, and control connections between said movable member and said regulating means including an element having a limited range of movement and movable in said range by frictional engagement with said member.

14. Apparatus for controlling a supply stream of fluid in response to changes in a characteristic of a portion of the fluid which has passed the point of supply control, said apparatus including a valve in said supply stream, reversible power means for moving said valve toward its open and closed positions, a control element movable from an intermediate position to positively limited positions in which respectively said power means are operated to move said valve in corresponding directions, a member positively movable in response to changes in said characteristic, said member having frictional engagement with said element so as to move said element to one or the other of its limiting positions, and spring means between said member and element tending to maintain said member and element in a predetermined relation to each other.

15. Apparatus for maintaining a pool of liquid at a substantially constant level during a continuous inflow and outflow of liquid into and out of said pool, said apparatus comprising a valve in the incoming stream, reversible power means for moving said valve toward its open and closed positions, and means responsive to changes in level of said pool for controlling said power means, said power controlling means including a float on said pool, a member positively movable by the rise and fall of said float, and an element frictionally engaged by said member and movable thereby between limiting positions in which respectively said element causes the actuation of said power means to move said valve correspondingly.

16. Apparatus for maintaining a pool of liquid at a substantially constant level during a continuous inflow and outflow of liquid into and out of said pool, said apparatus comprising a valve movable to regulate the rate of said inflow of liquid, reversible power means for moving said valve toward its open and closed positions, a float on said pool, a member movable positively by rise and fall of said float on said pool, and a control element movable by frictional engagement with said member in a narrow range between limiting positions, said control element having a normal intermediate position from which it is movable by a rise of the float to cause said power means to move said valve toward its closed position, said element being movable by a fall of said float to the opposite limiting position to cause said power means to move said valve toward its open position.
17. Apparatus of the class described comprising a vat for pulp stock having an inlet for the inflow of stock into said vat, a valve for regulating the inflowing stream, a float in said vat, valve-actuating means, and control connections between said float and said actuating means, said connections including an element having a narrowly limited range of motion and a second element positively movable by said float and in frictional engagement with said limited element.
18. A metering wheel of small size for a sampling stream of pulp stock, comprising an axis, a plurality of paddles projecting outwardly from said axis, the spaces between successive paddles being blocked off for a short distance from said axis.
19. A method of maintaining near a predetermined height the surface level of a pool having an inflow and outflow of liquid, and of minimizing the rate of variation of said level, which comprises varying the rate of inflow independently of the quantity of liquid present in the pool at any moment to oppose variation of surface level, and automatically controlling the variation of inflow in response to changes in direction of variation of level.
20. A method of maintaining substantially constant the quantity of a fluid in a body thereof having a supply stream adding fluid thereto and a discharge stream taking fluid therefrom, which comprises constricting or amplifying one of said streams independently of the quantity of fluid actually in said body at any moment, and controlling said constricting or amplifying action in response to changes in direction of variation of said quantity.
21. A method of maintaining substantially constant the level of a pool of liquid in a vessel to which liquid is being added through a supply port and from which liquid is being discharged, which comprises constricting the supply port in response to an upward drift of said level from normal until a downward drift sets in, maintaining said supply port unchanged during the downward drift to normal level unless the rate of said downward drift is excessive or deficient, and enlarging said port in response to excessive rate of downward drift or additionally constricting said port in response to deficient rate of downward drift toward normal, said method also comprising enlarging said supply port in response to a downward drift of level from normal until an upward drift sets in, maintaining said supply port unchanged during said upward drift to normal level unless the rate of said upward drift is excessive or deficient, and constricting said port in response to excessive rate of upward drift or additionally enlarging said port in response to deficient rate of upward drift toward normal level.
22. A method of delivering pulp stock at a substantially constant tonnage rate, which comprises maintaining a pool of stock, metering stock from said pool at a constant volume rate, providing a supply stream of stock for said pool, diluting the stock in the supply stream to the consistency desired, and admitting diluted stock to the pool at a rate substantially the same as the rate of discharge of the stock from the pool.
23. A method of delivering pulp stock at a substantially constant tonnage rate, which comprises maintaining a pool of stock, metering stock from said pool at a constant volume rate, providing a supply stream of stock, introducing diluting water into said stream, mixing said water thoroughly with the stock in said stream immediately prior to its entrance into said pool, regulating the rate of supply of diluting water to maintain the consistency of the mixed diluted stock substantially constant, and controlling the stock supply stream to maintain a volume rate of admission of diluted stock into said pool substantially equal to the rate at which the stock is metered from the pool.
24. A method of delivering pulp stock at a substantially constant tonnage rate, which comprises maintaining a pool of stock, metering stock from said pool at a constant volume rate, providing a supply stream of stock, introducing diluting water into said stream, mixing said water thoroughly with the stock in the stream, regulating the rate of addition of water to maintain the consistency of the mixed diluted stock substantially constant, admitting the diluted stock to the pool, and regulating the flow of the supply stream of undiluted stock so that its flow added to that of the diluting water substantially equals the discharge flow from the pool.
- In testimony whereof I have affixed my signature.
